US0D1054489S

(12) **United States Design Patent** (10) Patent No.: **US D1,054,489 S**
(45) Date of Patent: ** Dec. 17, 2024

(54) **LASER PRINTER**

(71) Applicant: **Zhuhai Pantum Electronics Co., Ltd.**,
Zhuhai (CN)

(72) Inventors: **Aiguo Yin**, Guangdong (CN); **Jibing Peng**, Guangdong (CN); **Geng Wang**, Guangdong (CN); **Ke Mou**, Guangdong (CN); **Yanliang Du**, Guangdong (CN); **Guangyu Fu**, Guangdong (CN)

(73) Assignee: **Zhuhai Pantum Electronics Co., Ltd.**,
Zhuhai (CN)

(**) Term: **15 Years**

(21) Appl. No.: **35/517,528**

(22) Filed: **Apr. 25, 2023**

(80) **Hague Agreement Data**

Int. Filing Date: **Apr. 25, 2023**

Int. Reg. No.: **DM/229423**

Int. Reg. Date: **Apr. 25, 2023**

Int. Reg. Pub. Date: **Jun. 16, 2023**

(30) **Foreign Application Priority Data**

Oct. 25, 2022 (CN) 202230706396.7

(51) **LOC (14) Cl.** **14-02**

(52) **U.S. Cl.**

USPC **D18/55**

(58) **Field of Classification Search**

USPC D18/50, 53-56, 59, 36-41, 45-49;
D14/121, 301, 307, 420, 421
